CHIMNEY CAP

Emil Zimmerman, Everett, Wash.

Application November 1, 1939, Serial No. 302,354

10 Claims.

(Cl. 98—78)

My invention relates to a chimney cap, that is, a device intended for application to the upper end of a chimney or other flue pipe, for the dual purpose of preventing down drafts, which sometimes occur from adverse wind or atmospheric conditions, and of employing the available wind, whether strong or light, and from whatever direction, to assist in creating an upward draft, and thereby to assist in withdrawing the smoke or other fumes from the flue for discharge to the atmosphere.

Devices for such purposes, in one form or another, have long been in common use. Frequently they take the form of a rotatable cap which is intended to be rotated by the wind to dispose the device in such a direction that the down draft is prevented from sweeping down into the flue, and that the wind may, to some degree, assist in withdrawing the smoke and gas from the flue. Such rotatable caps, however, have certain definite and well known objections, not the least of which is that being exposed to the weather and being generally of inexpensive sheet metal construction, they shortly begin to rust and stick, and then are worse than no cap.

Devices for such purposes as heretofore known have also taken the form of concentric conical and frusto-conical structures in various combinations, surmounting the chimney, the surrounding sleeves being open to the wind, the whole arranged with the intent that the wind entering at the lower end of such sleeves will pass out at the upper end and will tend to create something of an upward eductor effect, tending to withdraw the smoke and gas from the flue round about a central inverted conical deflector, but such devices have been found lacking in practical application in that the wind will not follow the intended path, but will tend to sweep generally horizontally around the conical deflector, wherefore its eductor effect is minimized, and whereby the wind itself may tend, by eddy currents, to interfere with the up draft, rather than to assist in creating the up draft.

It is the object of my invention, therefore, to provide a device for application as an immovable cap to a chimney or other flue, which, having no moving parts, is not subject to the objections attaching to the rotary caps, and which is so constructed as to avoid the drawbacks of the type last mentioned above, and which will accomplish efficiently the common aim of all such devices.

More specifically, it is an object of the present invention to provide a cap for the purpose in-

10 dicated, which so controls the movement of the wind that the wind is caused to move through the device in such a way that it is hardly possible to create eddy currents or down drafts into the flue, and in such a way that the wind cannot sweep through the cap in any manner except such as will induce an upward draft through the flue; in other words, it is an object to produce a device for such a purpose, which is so constructed as to prevent, positively, mere sweeping through of the wind around and about deflectors in a manner not intended, and not productive of the desired final up draft within the flue.

It is a further object to provide such a cap 15 which while not rotary, is open in all directions, so that it will operate from whatever quarter the wind may come, yet will function as intended, regardless of the wind's direction; which is positively closed against direct down drafts or through drafts of any sort; in which the internal parts are protected and not likely to collect rain water; in which the air currents and the smoke currents are guided and afforded ample passage areas; and which may be simply and ruggedly 20 constructed of sheet metal, and which may therefore be inexpensively constructed.

With these and other objects in mind, as will appear as the specification progresses, my invention 25 comprises the novel chimney cap and the novel construction and arrangement of the several parts thereof, as shown in the accompanying drawing in a preferred form, and as will be more fully disclosed in this specification and defined by the claims.

30 Figure 1 is a top plan view, with parts broken away, of the chimney cap.

Figure 2 is a cross section on a vertical plane, substantially on the line 2—2 of Figure 1.

Figure 3 is an isometric view, with parts broken away to illustrate the interior construction.

The device is formed as an upstanding collar 1, which is preferably of square or rectangular form in cross section, to fit upon and extend upwardly from the chimney 9. At its base it may 45 be variously formed to fit upon the chimney, as for instance by providing it with the sleeve 10. The particular formation of the collar in this respect is immaterial. It is only to be noted that it is carried by and extends upwardly from the chimney 9, substantially in line with the chimney flue 91, and that the collar, being of sheet metal, and of about the cross-sectional area of the exterior of the chimney, has an internal cross-sectional area considerably in excess of the area 50 of the flue 91.

At its top the collar 1 is closed by a plate or top 12, which is preferably relatively flat, so that it creates no appreciable change of direction of the wind flowing over it, and just below the top it is provided with openings 11 in each of its four sides, for entrance of wind and for exit of wind and smoke. These openings lie in the upper half of the collar, and the total area of each is approximately equal to the cross-sectional area of the flue 91. Instead of one continuous aperture 11, several individual apertures may be provided, if preferred. It appears more desirable, however, to employ one individual aperture in each face or wall of the collar, rather than several smaller apertures in each wall.

In its interior the collar 1 is divided by two partitions 2, which extend diagonally from corner to corner, and therefore cross in the center of the collar, their junction forming a vertical centrally disposed line 21. These partitions 2 extend, unbroken and imperforate, from the top plate 12 downwardly to a level at 20 below the lower edge of the apertures 11. They divide the upper portion of the interior of the collar into four sectors, and each of these sectors has, in the side wall of the collar, one of the apertures 11, but only one such aperture.

A hollow, inverted, pyramidal deflector 3, formed of sheet metal or the like, is centrally disposed within the collar, the marginal edges 30 of its base being spaced from the adjacent walls of the collar preferably, to provide smoke outlets of ample cross-sectional area as compared to the flue's cross section, and these marginal edges 30 are located above the lower edges 20 of the partitions 2, but preferably below the lower edges of the apertures 11 so that the sides of the pyramid are inclined upwardly and outwardly in alignment with the corresponding apertures, the drawing showing such deflector sides directed toward substantially the center of such openings. The margins 30, therefore, lie between the lower edges 20 of the partitions and the lower edges of the apertures 11. The interior of this pyramidal deflector 3 admits to each one of the sectors defined by the cross partitions 2, yet its margin 30 is above the bottom 20 of each sector. The term "pyramidal" is used generically to embrace pyramids having any number of sides, unless otherwise specified, so that it would include a conical shape, since a cone is merely a special type of pyramid, namely, a regular pyramid having an infinite number of triangular lateral surfaces. Preferably a four sided pyramid is used, as shown, with each edge 30 disposed parallel to a side of the square or rectangular collar 1.

As a refinement, preferably employed, curved baffles 4 may be provided in each sector, curving inwardly and downwardly from the upper edge of each aperture 11 towards the junction of the line 21 with the lower edges 20 of the partitions, or towards the apex of the deflector 3. Though it is considered undesirable to permit the partitions 4 to extend below the level of the edge 20, yet it is not outside the scope of the invention to permit this, provided there is still left ample cross-sectional area in each sector between the edge 30 therein and the partitions 2 which define the sector.

It is also desirable to afford baffles 5 which extend outwardly and which are preferably somewhat inclined upwardly from the upper edge of each aperture 11. These baffles 5 may be formed of the metal which is otherwise removed to form the apertures 11, bent outwardly and upwardly.

These baffles 5 serve to entrap and direct inwardly air which might otherwise pass over the top of the cap, and they serve much as do awnings to deter or prevent the entrance of rain water.

- 5 Smoke rising from the flue 91 will tend, if not acted upon by air currents or down drafts, to divide at the deflector 3 and to pass out on all sides thereof and into each one of the sectors, and thence out through the apertures 11. However, if the air is moving, whether the wind be light or strong, it tends to enter as indicated by the arrow A in Figure 2, and for the moment we may assume that the air direction is perpendicular to the face of the collar which contains the aperture at the left of Figure 2. The air entering at A is deflected downwardly and caused to converge into the angle of the partitions 2 by unbroken partitions and the curved interior baffle 4. However, it moves inward sufficiently that 10 it passes inside the margin 30 of the deflector 3, and has no appreciable tendency to pass downward between this margin 30 and the left-hand wall of the collar. Entering the deflector 3, it can only escape by reversing its direction and 15 moving upwardly, as indicated by the arrow B, and then in the opposite sector, at the right, it tends to pass out through the upper portion of the aperture 11, as indicated by the arrow C, being aided in its change of direction by the wall of the deflector 3 and by the curved interior baffle 4 in the right-hand sector. Thus its direction is necessarily upward and outward, and it thereby 20 entrains the smoke from the flue 91, which now tends to rise into the right-hand sector, as indicated by the arrow D, and this smoke, directed outwardly by the side of the deflector, passes out of the lower portion of the aperture 11 as indicated by the arrow E, aided by the aspirating effect of the air also passing through the aperture. 25
- 20 The cross-sectional areas of the restricted portions of these passages are sufficient to afford the movement of air or smoke as indicated, without appreciable restriction of flow nor tendency to eddy.
- 25 While opposite sides of the collar preferably are disposed parallel to the prevailing wind, the direction of the wind is not always perpendicular to any given face or wall of the collar 1, but at times will be at an angle thereto. Let us assume 30 that it is at 45°, and thus equally strikes two adjoining perpendicular walls of the collar. It tends to enter the aperture 11 in each of these walls, but can not pass immediately through and 35 out the apertures in the opposite walls, because it is intercepted and blocked by the imperforate diagonal partition 2, and is directed downwardly by the curved interior baffles 4, and is caused to converge to the junction 21 of the partitions 2, wherefore it is caused to enter the conical deflector 3, and to pass downwardly thereinto, and 40 then upwardly again, but at the opposite side of the partition first encountered. Passing upward only at the opposite side of this partition, this wind can only pass out of the apertures 11 at the opposite side of such partition. Thus it follows, 45 from the use of the cross partitions 2, that the air must always, wholly or certainly in a major part, pass into the conical deflector 3 before it can pass upwardly, that it can only pass upwardly because it is so directed and because the only escape is above, and when it passes upwardly it can only pass outwardly at the opposite side of the partition or partitions which barred its through passage; from all this it follows that the 50 wind, in escaping, must entrain smoke from the 55
- 55
- 60
- 65
- 70
- 75

flue 91. Down drafts are thus prohibited, and the wind, whether light or heavy, will automatically and of necessity entrain upward movement of the smoke.

What I claim as my invention is:

1. A chimney cap comprising a collar formed as an upward extension of the chimney, and closed at its top, having openings in all its sides adjacent its top, upright partitions extending across the interior of the collar, subdividing it into at least four sectors, the partitions extending from the closed top downwardly to a level below said openings, and being imperforate throughout such extent, whereby communication between sectors can be had only beneath the partitions, and a hollow, inverted pyramidal deflector disposed with its apex spaced beneath the juncture of the partitions, the edges of said pyramidal deflector being disposed above the level of the lower edge of the partitions, and inwardly from the walls of the collar, to leave an annular smoke passage, and such edges being further disposed outwardly of the juncture of the partitions, to direct air which enters at one opening downwardly at the corresponding side of the partitions and then upwardly at the other side thereof, for discharge with entrained smoke, through an opening at such other side.

2. A chimney cap comprising a collar formed as an upward extension of the chimney, and closed at its top but laterally open on all sides adjacent its top, imperforate partitions fixed within the collar, extending from its closed top downward completely through and to a level below its laterally open portion, and intersecting at about the center line of the collar to divide the same lengthwise into at least four substantially equal sectors, and a hollow, inverted pyramidal deflector disposed with its apex spaced beneath the junction of the lower edges of the partitions, and with its basal edges extending between adjacent partitions, and spaced from the adjoining collar wall to afford a smoke passage from the flue beneath, in each sector.

3. A chimney cap comprising a collar formed as an upward extension of the chimney, and closed at its top but laterally open on all sides adjacent its top, imperforate partitions fixed within the collar, extending completely through its laterally open portion and downward below such portion, and dividing the collar lengthwise into at least four sectors, a hollow inverted pyramidal deflector disposed with its apex spaced beneath the partitions, and with its basal margin above the lower edges of the partitions, and spaced inside the walls of the collar, to afford a smoke passage from the flue beneath into each sector, and a baffle in each sector curving from a point adjacent the upper edge of each opening inwardly towards the partitions forming such sector and downwardly at least to a location substantially even with the lower edge of the collar opening.

4. A chimney cap comprising a collar closed at its top, and formed as an upward extension of the chimney, and laterally open on all sides adjacent its top, two imperforate vertical partitions fixed in intersecting relationship within the collar, extending from its closed top downwardly through its laterally open portion and to a level below the lower edge of the collar opening, dividing the collar lengthwise into four sectors, and a hollow inverted pyramidal deflector disposed with its apex spaced beneath the intersecting

line of the partitions, and with its sides lying in planes which are directed upwardly and outwardly to intersect the collar in a line substantially above the lower edge of the corresponding collar opening, the deflector's sides stopping short of the collar to dispose the deflector's upper edges above the lower edges of the partitions but below the lower edges of the openings, and spaced inside the walls of the collar, to afford a smoke passage from the flue beneath said deflector through each sector directed outwardly toward the collar opening.

5. A chimney cap comprising a collar which is rectangular in cross section, formed as an upward extension of the chimney flue, said collar being closed at its top but laterally open at the top of each wall of the collar, two imperforate, diagonal, vertical, fixed partitions extending from its top closure downwardly and from corner to corner within the collar, crossing at its center, and dividing the collar lengthwise into four sectors, and an inverted, hollow, rectangular pyramidal deflector disposed with its apex spaced below the junction of the partitions, and with its basal edges above the lower edge of the partitions, each base edge of the deflector bridging between the adjacent partition portions and disposed parallel to and spaced from the collar wall in a sector to afford a smoke passage from the flue beneath into each sector.

6. A chimney cap comprising a collar which is rectangular in cross section, formed as an upward extension of the chimney flue, said collar being closed at its top but laterally open at the top of each wall of the collar, two imperforate, diagonal, vertical, fixed partitions extending from its top closure downwardly and from corner to corner within the collar, crossing at its center, and dividing the collar lengthwise into four sectors, an inverted, hollow, rectangular pyramidal deflector disposed with its apex spaced below the junction of the partitions, and with its basal edges above the lower edge of the partitions, each base edge of the deflector bridging between the adjacent partition portions and disposed parallel to and spaced from the collar wall in a sector, to afford a smoke passage from the flue beneath into each sector, and a baffle in each sector curving from the upper edge of each collar opening inwardly into the angle between the partition portions forming such sector and downwardly at least to a location substantially even with the lower edge of the collar opening.

7. A chimney cap comprising a collar which is rectangular in cross section, formed as an upward extension of the chimney flue, said collar being closed at its top but laterally open at the top of each wall of the collar, two imperforate, diagonal, vertical, fixed partitions extending from its top closure downwardly and from corner to corner within the collar, crossing at its center, and dividing the collar lengthwise into four sectors, an inverted, hollow, rectangular pyramidal deflector disposed with its apex spaced below the junction of the partitions, and with its basal edges above the lower edge of the partitions, each base edge of the deflector bridging between the adjacent partition portions and disposed parallel to and spaced from the collar wall in a sector to afford a smoke passage from the flue beneath into each sector, and a baffle for the collar opening including a portion in each sector curving from the upper edge of each collar opening inwardly into the angle between the partition

portions forming such sector and downwardly at least to a location substantially even with the lower edge of the collar opening, and also a portion extending from the collar upwardly and outwardly in continuation of said first baffle portion.

8. A chimney cap comprising a collar formed as an upward extension of the chimney, and closed at its top, having openings in all its sides adjacent its top, upright partitions extending across the interior of the collar subdividing it into at least four sectors, the partitions extending from the closed top downwardly to a level below said openings, and being imperforate throughout such extent, whereby communication between sectors can be had only beneath the partitions, and a hollow, inverted pyramidal deflector disposed with its apex spaced beneath the juncture of the partitions, the edges of said pyramidal deflector being disposed above the level of the lower edge of the partitions, and inwardly from the walls of the collar, to leave an annular smoke passage, and such edges being further disposed outwardly of the juncture of the partitions, to direct air which enters at one opening downwardly at the corresponding side of the partitions and then upwardly at the other side thereof, for discharge, with entrained smoke, through an opening at such other side, and a baffle in each sector curved, from a level with the upper edge of the corresponding opening, inwardly and downwardly, and disposed generally transverse to air entering at such opening, to direct air entering by such opening inwardly and downwardly towards the apex of said inverted pyramidal deflector, or to direct air rising from such deflector outwardly through such opening.

9. A chimney cap comprising a collar formed as an upward extension of the chimney, closed at its top, and having openings on all sides adjacent its top, relatively crossed upright partitions extending diametrically from side to side across the interior of the collar, and from its top closure

downwardly to a level below the collar's openings, and being imperforate throughout such extent, said crossed partitions dividing the interior of the upper portion of the collar into sectors, between 5 which communication can only be had beneath the lower edges of said partitions, and a hollow, inverted pyramidal deflector disposed with its apex spaced beneath the juncture of the partitions, and with its sides directed upwardly and outwardly towards the openings, but terminating in edges which are spaced above the lower edges of the partitions but not above the lower edges of the collar's openings, and intermediate the side walls of the collar and the juncture of the partitions, thus to define smoke passages from the flue 10 between the deflector's edges and the collar's side walls, and to define a separate passage, first directed downwardly and then upwardly, for air which enters at an opening at one side of the collar, and directing it outwardly through the opening at the other side thereof.

10. A chimney cap comprising a collar formed as an upward extension of the chimney, and closed at its top but laterally open on all sides 25 adjacent its top, imperforate partitions fixed within the collar and dividing it into at least four sectors, a hollow, inverted pyramidal deflector disposed with its apex spaced beneath the partitions, and with its sides directed upwardly 30 and outwardly towards the corresponding collar opening, but stopping short thereof to dispose its upper edges in spaced relation to the walls of the collar, to afford a smoke passage from the flue beneath said deflectors through each sector directed outwardly toward the collar opening, and 35 means between said partitions and the collar, disposed opposite each opening, operable to deflect air flowing in through any opening downward alongside a partition into said hollow inverted deflector.

EMIL ZIMMERMAN.
